UNITED STATES PATENT OFFICE.

FREDERICK W. PENDERGAST, OF CAMBRIDGE, MASSACHUSETTS.

MOP.

1,099,858.

Specification of Letters Patent.

Patented June 9, 1914.

Application filed May 5, 1913. Serial No. 765,447.

To all whom it may concern:

Be it known that I, FREDERICK W. PENDERGAST, a citizen of the United States, and a resident of Cambridge, in the county of 5 Middlesex and State of Massachusetts, have invented certain new and useful Improvements in Mops, of which the following is a specification.

This invention relates to mops composed 10 of fibrous strands of cotton yarn or thread adapted to be detachably secured to a handle.

The invention has for its object to provide 15 a mop of this character of simple and relatively inexpensive construction adapted to be manufactured without the employment of special appliances.

The invention consists in the improvements which I will now proceed to describe 20 and claim.

Of the accompanying drawings: Figure 1 represents a side view illustrating the first stage of operation of making my improved mop. Fig. 2 represents a section on line 25 2—2 of Fig. 1. Fig. 3 represents a view similar to Fig. 1 showing the second stage of the operation. Fig. 4 represents a side view of the complete mop and a portion of the handle adjacent thereto. Fig. 5 represents 30 a view of the inner end of the mop as shown by Fig. 4. Fig. 6 represents a section on line 6—6 of Fig. 5. Fig. 7 represents a perspective view of the part hereinafter called the hub.

35 The same reference characters indicate the same parts in all the figures.

In the drawings:—12 represents a hub which is preferably made of a malleable metal such as malleable iron or brass, and is adapted 40 to detachably engage a handle 13, the hub being preferably provided with a screw threaded socket 14 adapted to engage a screw threaded shank 15 on the handle. The end portions of the hub are enlarged by means 45 of a flange 16 on the outer end of the hub and ears 17 on the inner end of the hub, said ears being preferably forked as shown by Fig. 7. The ears project in opposite directions from the hub and the outer ends of 50 their prongs are inclined inwardly toward each other to confine between the prongs groups of fibrous strands inserted in the recesses between the prongs. Around the hub 12 I group a multiplicity of elongated 55 fibrous strands 18 as shown by Fig. 2, the strands being laid side by side with their

central portions covering the hub and their end portions projecting at substantially equal distances from the hub. Groups of the strands are pressed into the recesses between the prongs of the ears 17 and are closely confined in said recesses, the malleability of the prongs enabling their points to be bent inwardly toward each other to more closely confine said groups. I next 60 bind the central portions of the strands upon the hub by means of a ligature 19 preferably of wire, which compresses the central portions of the strands between the enlargements 16 and 17 as shown by Fig. 3. By 65 thus confining the strands I convert them into two series of mop filaments which at this stage of the operation project in opposite directions from the ends of the hub. I then bend backwardly the filaments of one 70 series, namely, that projecting from the outer end of the hub, over the ligature 19 as shown by Figs. 4 and 6, thereby exposing the outer end of the hub, the backwardly bent series of filaments covering the other series 75 of filaments between the prongs of 80 the ears 17 support the backwardly bent filament portions, so that the latter cannot be pressed inwardly far enough to permit the outer ends of the prongs to project from the exterior of the mop and injure mop boards 85 or other surfaces with which the mop comes in contact. Some of the filaments of both 90 series are engaged with the ears 17, numerous filaments entering the spaces between the prongs of said ears and others bearing 95 on the outer edges of the ears. The mass of filaments is therefore prevented from turning on the hub.

20 represents a bridle of cloth or other suitable flexible material which surrounds 100 the mass of filaments near the hub and is secured thereto by stitches 21, the bridle confining the backwardly bent series of filaments upon the inner series.

The mop thus constructed is adapted to be 105 manufactured to good advantage by blind people and is relatively inexpensive, so that when the filaments are worn nearly to the hub, the mop may be removed from the handle and discarded, a new mop being substituted for it.

The ears 17 projecting from opposite sides

of the hub constitute forming members, or spreaders, which impart an approximately elliptical form to the inner end portion of the mop as indicated by Fig. 5, the mop having two relatively wide approximately flat sides.

What I claim and desire to secure by Letters Patent is:—

A mop comprising a handle-engaging hub having forked malleable metal ears, projecting from opposite sides of the hub, the outer ends of the prongs of said ears being inclined inwardly, elongated fibrous strands laid side by side, their central portions being grouped around and covering the hub, some of the strands being grouped and confined between the prongs of said ears, a ligature surrounding the central portions of the strands and binding them upon the hub, the

end-portions of the strands forming two series of mop filaments, one of which is bent backwardly over the ligature to expose the outer end of the hub and cover the other series and all portions of the ears whereby a thick flexible mass of filaments is formed 25 extending from the hub said mass being given an approximately flat sided form by the ears, and a bridle surrounding and secured to said mass and confining the backwardly bent series of filaments. 30

In testimony whereof I have affixed my signature, in presence of two witnesses.
